HEAT EXCHANGE APPARATUS

Anthony J. Larrecq, Beach Bluff, Mass., assignor
to General Electric Company, a corporation of
New York

Application February 17, 1938, Serial No. 191,047

12 Claims. (Cl. 257—25)

The present invention relates to heat exchange apparatus for use with motor vehicles. Although not limited thereto, the invention is especially applicable to locomotives which are 5 driven directly or indirectly by means of an elastic operating fluid such as steam which is desired to be continuously re-condensed and re-utilized.

It is an object of the invention to provide an air 10 cooled heat exchanger apparatus capable of condensing the exhaust fluid of the locomotive engine with very little loss of such fluid thereby to reduce to a small value the amount of make-up fluid necessarily supplied during a given run of the 15 locomotive.

A further object is to provide a surface type condenser which will operate efficiently under the conditions encountered in a locomotive or other motor vehicle.

20 In the preferred embodiment of the invention, as applied to a locomotive, the heat exchange apparatus comprises a condenser arranged in the upper portion of the vehicle adjacent the roof and after-cooler sections arranged adjacent the outer 25 side walls of the vehicle in such a way as to permit air to be drawn through inlets in such walls, forced across the heat exchange surfaces thereof, and discharged through the roof of the vehicle by means of a blower appropriately arranged.

30 The condensate is collected in a reservoir arranged in the vehicle floor. By this arrangement, a very efficient operation of the heat exchange apparatus is obtained, since the cooling air passes first over the after-cooler sections and 35 then over the condenser section. As a result, a very complete separation of the condensable vapor and the non-condensables takes place and correspondingly little fluid has to be supplied to the system for make-up purposes.

40 For a consideration of what I believe to be novel and my invention, attention is directed to the following description and the claims appended thereto in connection with the accompanying drawings.

45 In the drawings, Fig. 1 is a diagrammatic view of a complete locomotive exemplifying one application of the invention; Fig. 2 is a sectional view taken along line 2—2 of Fig. 1 and shows further aspects of the condensing apparatus arrangement; Fig. 3 is a side view of a section of the condenser arrangement taken through the line 3—3 of Fig. 2; Fig. 4 is a fragmentary section detail through a group of the condenser tubes appearing in Figs. 2 and 3; and Fig. 5 is a

fragmentary detailed view in section of the condenser supporting means shown in Fig. 2.

Since it is particularly adaptable for such use, the invention will be described as applied to a turbo-electric locomotive, that is, a locomotive 5 which employs an elastic fluid turbine as a prime mover and an electric generator and motor combination for transmitting the energy developed by the prime mover to the driving wheels of the locomotive. By condensing the exhaust fluids of 10 the turbine, a low back pressure may be maintained and high turbine cycle efficiency realized. Furthermore, the rate at which make-up fluid must be supplied may be reduced to a low value so that long continuous runs without rewatering 15 become possible, this being a factor of considerable importance in maintaining high speed locomotive schedules.

The locomotive which is illustrated in Fig. 1 as being of the reversible type comprises a cab structure 10 supported on trucks 11 and 12 having a pair of similar power plant units 13 and 14 arranged at opposite ends of the locomotive structure. For the present purposes, only one unit will be described since the two units are substantially 20 identical. The power plants include a boiler 15 preferably heated by a liquid fuel burner, not shown, an elastic fluid turbine 16 and an electric generator 17 connected to the turbine in any suitable manner. The power developed by the generator 25 is transmitted to electric motors, not shown, which are mechanically connected to the driving 30 wheels of the locomotive.

The elastic fluid flows from the boiler 15 through a conduit 18 through the turbine 16 and 35 exhausts through the conduit 19 into the main condenser section 20 disposed in the upper portion of the vehicle immediately adjacent the cab roof. The admixed condensate and non-condensable pass from the main condenser 20 through connections 21 to a pair of after-cooler 40 sections 22 disposed in the opposite side walls of the locomotive cab, these being drained by conduits 23 into the reservoir or hot-well 24 from which the condensate is returned to the boiler by 45 means of a pump 25 and conduit 26.

As shown in Fig. 3, the main condenser comprises a transverse inlet header 27 and a parallel outlet header 28 longitudinally spaced apart and an intermediate header 29 located substantially midway therebetween. A plurality of heat exchange tubes 30 extend longitudinally between the headers and are arranged at a slight angle so that they slope toward the outlet end, to insure proper drainage of the condensate therefrom. 50 55

The tubes are provided with fins 31 in a well-known manner to increase the heat radiating surface thereof. The elastic fluid entering the inlet header 27 through the exhaust conduit 19 passes through the first section of heat exchange tubes 30 where partial condensation takes place, these tubes draining into the intermediate header 29. Condensate is drained from the intermediate header 29 by means of a conduit 32 communicating therewith into the hot-well 24. The remaining elastic fluid passes then into the second section of heat exchange tubes where further condensation takes place, these tubes draining into the outlet header 28. The condenser unit is so arranged and shaped, as indicated, to conform with the shape of the roof to utilize advantageously the available space therebeneath. As viewed in Fig. 2, due to the arch of the roof, the depth of the condenser section is considerably less at the sides than in the central portion. Accordingly, at the sides where the condenser is only a few tubes deep, the tubes are relatively closely spaced. Likewise in the central section where the depth of the condenser is considerable, the tubes are more widely spaced apart so that the resistance to air flow is substantially uniform throughout the width of the condenser unit. Under such conditions, the temperature rise of the cooling air is substantially uniform across the condenser surface.

From header 28, the condensate together with any remaining traces of vapor and admixed non-condensables pass through connections 21 into the after-cooler sections 22 where separation is completed. The after-cooler sections 22 disposed adjacent the opposite side walls 33 immediately below the main condenser 20 comprise upper headers 34 and lower headers 35 having a plurality of vertically arranged heat exchange tubes 36 communicating therewith. The side walls 37 are provided with openings protected by louvers through which cooling air passes and circulates over the surface of the tubes 36. The cooling air coming first into contact with the after-cooler sections completes the separation of the condensable vapors and the non-condensable gases which pass from the lower headers of these sections through the conduits 23 into the hot-well 24 located in the floor of the cab structure. The non-condensables are drawn from the hot-well 24 through a connection 39 by any suitable ejector or pumping means, not shown.

Under certain conditions it may be desirable to improve the characteristics of the condenser by spraying the tubes thereof with an evaporative fluid, such as water. Means for accomplishing this result are illustrated as comprising a series of spray tubes 40 which extend at spaced intervals longitudinally through the condenser section. As shown in Fig. 3, these spray tubes are connected by a supply conduit 41, and are so perforated as indicated in Fig. 4, at 42 and so spaced with respect to the condenser tubes that the jets of water therefrom contact with substantially all of the heat exchange tubes of the section.

Expansion considerations and the types of vibration normally encountered in high speed locomotive operation make it necessary to provide for a certain degree of flexibility in the heat exchanger mounting so that at least some relative motion can take place between the heat exchanger units and the supporting framework of the vehicle without excessively stressing the heat exchanger parts. In accordance with the present invention the main condenser unit is resili-

ently supported upon the vehicle framework, as shown in the detail sketch, Fig. 5. The condenser headers 27, 28 and 29 are secured as by welding to a pair of parallel supporting members 43 extending along opposite sides thereof which are provided with extending flange portions 44. The flange portions are adapted to rest upon angle brackets 45 secured to the side walls 33 of the vehicle through intermediate resilient supporting means 46. A pin 47 which is secured as by welding to the angle bracket 45 through an anchoring disk 48, extends upwardly through an aperture 49 provided in the flange portion 44. A plurality of annular disks 50 of resilient material, such as rubber, provided at their inner and outer peripheries with annular metallic spacer rings 51, are mounted on the pin, held between a shoulder 52 thereon and a nut 53 threaded onto the upper end thereof. A cylindrical member 54 is secured as by welding to the upper surface of the flange portion 44 around the aperture 49, and engages and positions the disks so that the pin 47 is retained in a spaced relationship with the edges of the aperture 49. A cap 55 is threaded into the upper portion of the cylinder, the shoulder 56 of which engages the outer spacer ring of the upper disk and clamps the assembly of disks so that the flange 44 is supported spaced from the vehicle frame member 45 and the anchor ring 48. By this arrangement, there is no metal to metal contact between the condenser unit 20 and the supporting structure, so that vehicular vibrations and stresses are effectively insulated. The after-cooler sections 22 are supported at their lower ends upon angle brackets 57 secured, as by welding to the side walls of the vehicle, suitable apertures 58 being provided in the horizontal portion of the bracket for the passage of the drain conduits therethrough. The upper ends of the after-cooler sections are retained in position by resilient means which allow for the expansion of the sections, and prevent the transmission of injurious stresses from the vehicle body to the sections. As shown in Fig. 5, a cushion 59 of resilient material, such as rubber, is held by a suitable retainer member 60 which in turn is fastened, as by welding, to the underside of bracket 45. A metal section 61 moulded into the central portion of the cushion provides a bearing surface for a cooperating lug 62 extending from the upper surface of the after-cooler header 34.

In order to force air through the heat exchange apparatus with the desired velocity, I may utilize one or more blowers arranged in a suitable manner between the after-cooler sections and the condenser unit. The particular form of blower illustrated comprises a set of vanes 63 which, as shown, may be driven by any suitable means such as a turbine 64. The turbine and blower are supported as by suitable brackets 65 extending from the side walls of the vehicle. As shown, the bracket 65 comprises a sheet of metal which forms a partition between the lower portion of the vehicle and the condenser compartment and substantially encloses the air passage between the side wall and the roof openings. A stationary liner 66 depending from the condenser supports is arranged around the blower vanes to provide an orifice therefor, a ring 67 at the lower edge thereof increases the rigidity of the arrangement. The cooling air is drawn through inlet louvers in the side walls, past the after-cooler tubes and is forced by the blower upwardly past the condenser tubes and is discharged 70 75 78 80 85 90 95 98 99 through an open grill work 68 suitably arranged in the roof of the vehicle, discharging it past the condenser and through the outlet opening.

The flow of air through the condenser structure may be regulated in accordance with certain operating conditions of the locomotive, conditions of temperature obtaining in the various units of the condenser system or in accordance with conditions of ambient temperature to provide for the most efficient operation of the system or to prevent freezing of condensate therein during subnormal temperatures. Such regulation may be effected by varying the speed of the blower driving turbine by suitable control apparatus or should it be more desirable to use a variable pitch blower, the regulation may be effected by varying the pitch of the blower blades.

Although I have described the heat exchange system in which the cooling air is drawn first through the after-cooler sections 22 and then forced through the main condenser section 20, it may be desirable, as during cold weather operation, to reverse the direction of air flow to prevent freezing of the condensate in the after-cooler tubes. The reversal of air flow may be effected by reversing the direction of rotation of the blower 63 or by shifting the blower blades. By thus reversing the direction of air flow, the temperature of the cooling air is raised in passing through the main condenser section 20 before it is discharged through the relatively colder after-cooler sections 22, thus obviating freezing of the condensate in those sections.

Having described my invention in what I now consider to represent the best embodiment thereof, I desire to have it understood that the apparatus shown is only illustrative and that the invention may be carried out by other means.

What I claim as new and desire to obtain by Letters Patent of the United States is:

1. In a motor vehicle having an elastic fluid engine mounted thereon, means for condensing the elastic fluid exhaust from said engine, said means comprising a condenser disposed adjacent the roof of the vehicle and a pair of after-cooler sections disposed along opposite sides walls of said vehicle adjacent said condenser, a blower arranged beneath said condenser for drawing air past said after-cooler sections and forcing said air upwardly past said condenser and a reservoir for condensate in the floor of the vehicle.

2. In a motor vehicle having an elastic fluid engine thereon, heat exchange means for condensing the elastic fluid exhaust from said engine, said means comprising a condenser disposed adjacent the roof of the vehicle, said condenser having inlet and outlet headers longitudinally spaced apart with respect to said vehicle, a plurality of heat exchange tubes communicating between said headers and sloping toward said outlet header, a pair of after-cooler sections disposed along opposite side walls of said vehicle, said after-cooler sections each comprising upper and lower headers having vertically arranged heat exchange tubes communicating therebetween, the upper headers of said after-cooler sections communicating with the outlet header of said condenser, a reservoir for condensate in the floor of the vehicle, a conduit extending from the lower headers of said after-cooler sections to said reservoir, inlets for air in the side walls adjacent said after-cooler sections, an outlet for air in the roof of said vehicle adjacent said condenser section, a blower positioned between said after-cooler sections and said condenser section for drawing air past said after-cooler sections and

discharging it past the condenser and through the outlet opening.

3. In a motor vehicle having an elastic fluid engine, means for condensing the elastic fluid exhaust from said engine, said means including a main condenser unit resiliently supported adjacent the roof of said compartment, said heat exchanger including longitudinally spaced apart inlet and outlet headers, heat exchanging tubing communicating with said headers and sloping from the inlet to the outlet header, a pair of after-cooler sections resiliently arranged along opposite walls of said compartment connected with said main condenser unit, said after-coolers comprising upper and lower headers, a plurality of heat exchange tubes between said headers, a reservoir for condensate in the floor of the compartment and a conduit for draining said lower headers of said after-coolers into said reservoir.

4. In a motor vehicle having an elastic fluid engine, heat exchange apparatus for condensing the elastic fluid exhaust from said engine, said apparatus comprising a condenser disposed adjacent the roof of the vehicle, said condenser having longitudinally spaced apart inlet and outlet headers, a plurality of heat exchange tubes connected between said headers and sloping toward said outlet header, an intermediate header between said inlet and outlet headers communicating with said heat exchange tubes, means for conducting condensate from said intermediate header, a pair of after-cooler sections communicating with the outlet header of said condenser disposed along opposite side walls of said vehicle, said after-cooler sections comprising upper and lower headers having vertically arranged heat exchange tubes communicating therewith, a reservoir for condensate in the floor of the vehicle connected with said intermediate header and said after-cooler sections, inlets for air in the side walls adjacent said after-cooler sections, an outlet for air in the roof of the vehicle adjacent said condenser section, a blower positioned between said after-cooler sections and said condenser section for drawing air past said after-cooler sections and discharging it past the condenser through the outlet opening and a plurality of tubes extending among the heat exchange tubes of said condenser for spraying said last mentioned tubes with an evaporative fluid such as water.

5. In a motor vehicle having an elastic fluid engine, heat exchange means for condensing the elastic fluid exhaust from said engine, said means comprising a condenser disposed adjacent the roof of the vehicle, the upper surface of said condenser being shaped to conform with the roof, said condenser having spaced apart inlet and outlet headers transversely arranged with respect to said vehicle, a plurality of heat exchange tubes connected between said headers and sloping towards said outlet header, said tubes being so spaced apart that the resistance to air flow past said tubes is substantially uniform across the surface of said condenser, and an intermediate header between said inlet and outlet headers communicating with said heat exchange tubes.

6. Heat exchange apparatus including a condenser having inlet and outlet headers, a plurality of heat exchange tubes connected between said headers and sloping toward said outlet header, an intermediate header between said inlet and outlet headers communicating with said heat exchange tubes, means for conducting condensate from

said intermediate and outlet headers and a reservoir for receiving such condensate.

7. Heat exchange apparatus including a condenser having horizontally spaced apart inlet and outlet headers, a plurality of heat exchange tubes connected between said headers and sloping toward said outlet header, an intermediate header parallel with said inlet and outlet headers communicating with said heat exchange tubes, means for conducting condensate from said intermediate and outlet headers, a plurality of spaced apart tubes extending between said heat exchange tubes for spraying said last mentioned tubes with an evaporative fluid such as water.

8. Heat exchange apparatus including a condenser having spaced apart inlet and outlet headers, a plurality of heat exchange tubes connected between said headers and sloping toward said outlet header, an intermediate header between said inlet and outlet headers communicating with said heat exchange tubes, means for conducting condensate from said intermediate header, an after-cooler section comprising an upper and a lower header having a plurality of heat exchange tubes communicating therebetween, a conduit connecting the outlet header of said condenser with the upper header of said after-cooler, a condensate reservoir positioned below said after-cooler section, a conduit for draining condensate from the lower header of said after-cooler into said reservoir, a conduit for removing non-condensables from said reservoir and means positioned between said condenser and said after-cooler for forcing cooling fluid into contact with the tubes of said condenser and said after-cooler.

9. In a motor vehicle having an elastic fluid engine, heat exchange means for condensing the elastic fluid exhaust from said engine, said means comprising a heat exchanger disposed adjacent an opening in the roof of said vehicle, inlet and outlet headers for said heat exchanger arranged transversely of said vehicle, a pair of heat exchangers arranged adjacent openings in the opposite walls of said vehicle, said pair of heat exchangers each having an upper inlet header and a lower outlet header and conduit means communicating between the outlet header of said first heat exchanger and the inlet headers of said pair of heat exchangers.

10. In a motor vehicle having an elastic fluid engine, heat exchange means for condensing the elastic fluid exhaust from said engine, said means comprising a heat exchanger disposed adjacent an opening in the roof of said vehicle and extending longitudinally with respect thereto, inlet

and outlet headers for said heat exchanger arranged transversely of said vehicle, the opposite ends of said headers being resiliently supported on the side walls of said vehicle, a pair of heat exchangers arranged adjacent openings in the opposite side walls of said vehicle, said pair of heat exchangers each having an upper inlet header and a lower outlet header, a conduit connection between the outlet header of said first heat exchanger and the inlet headers of said pair of heat exchangers, and blower means for circulating air through said heat exchangers.

11. In a motor vehicle having an elastic fluid engine, heat exchange means for condensing the elastic fluid exhaust from said engine arranged within a compartment in the upper portion of said vehicle, said means comprising a heat exchanger disposed adjacent an opening in the roof of said vehicle, inlet and outlet headers for said heat exchanger arranged transversely of said vehicle, a pair of heat exchangers arranged within said compartment adjacent openings in the opposite side walls of said vehicle, and having inlets adjacent said outlet header, means for conducting elastic fluid from said outlet header to the inlet of each of said pair of heat exchangers, means defining an air passage between said side wall and said roof openings and substantially partitioning said heat exchanger compartment from the remainder of said vehicle, and means arranged in said air passage for circulating cooling air through said heat exchangers.

12. In a motor vehicle having an elastic fluid engine, heat exchange means for condensing the elastic fluid exhaust from said engine arranged within a compartment in the upper portion of said vehicle, said means comprising a first heat exchanger longitudinally arranged adjacent an opening in the roof of said vehicle, inlet and outlet headers for said first heat exchanger arranged transversely of said vehicle and supported upon the opposite side walls thereof, a pair of heat exchangers arranged within said compartment adjacent openings in the opposite side walls of said compartment, means for conducting the uncondensed elastic fluid from said first heat exchanger to each of said pair of heat exchangers, a blower arranged beneath said first-mentioned heat exchanger and between said oppositely disposed heat exchanger for circulating cooling air therethrough, and means including the support for said blower substantially enclosing the air passage between said side wall and said roof openings.
